United States Patent Office

Des. 213,859
Patented Apr. 22, 1969

213,859

CAN

Stanley Belitzky, Ville St. Laurent, Quebec, Canada, assignor to Bell Designs, Inc., Montreal, Quebec, Canada

Filed Mar. 4, 1968, Ser. No. 10,817

Term of patent 14 years

Claims priority, application Canada Mar. 2, 1968

Int. Cl. D9—01, 07
U.S. Cl. D9—43

FIGURE 1 is a top plan view of a can embodying my new design;

FIGURE 2 is a front elevational view;

FIGURE 3 is a bottom plan view;

FIGURE 4 is an elevational view looking from the right of FIGURE 2;

FIGURE 5 is a rear elevational view; and

FIGURE 6 is an elevational view looking from the left of FIGURE 2.

FIGURE 7 is a front elevational view of another embodiment of my new design; and

FIGURE 8 is a rear elevational view thereof;

FIGURE 9 is a top plan view thereof;

FIGURE 10 is a bottom plan view thereof;

FIGURE 11 is an elevational view looking from the right of FIGURE 7.

FIGURE 12 is an elevational view looking from the left of FIGURE 7.

The dominant features of my design reside in the portion shown in full lines.

I claim:

The ornamental design for a can, as shown and described.
